UNITED STATES PATENT OFFICE.

ARTHUR C. SOULE, OF SAN FRANCISCO, CALIFORNIA, ASSIGNOR TO SANITARY SCREEN AND SHADE COMPANY, OF SAN FRANCISCO, CALIFORNIA, A CORPORATION OF CALIFORNIA.

WINDOW-SCREEN.

1,201,885.

Specification of Letters Patent. Patented Oct. 17, 1916.

Application filed January 2, 1915. Serial No. 290.

To all whom it may concern:

Be it known that I, ARTHUR C. SOULE, a citizen of the United States, residing in the city and county of San Francisco, State of California, whose post-office address is 226 Judah street, have invented new and useful Improvements in Window-Screens, of which the following is a specification.

The invention relates more particularly to 10 sliding window screens adapted to close the entire window opening.

Among the objects sought to be accomplished are to provide a window screen, including a plurality of sections, slidable upon 15 each other; that is simple in construction and cheap to produce; that is easily installed within the window opening; and that is so constructed that it may be trimmed to fit window openings of various widths.

20 Other objects and advantages will appear as the description progresses.

In the drawing accompanying and forming part of the present specification, to which like reference characters have been 25 applied, a simple form of putting this invention into practice is shown. I do not wish to be understood as confining this invention to the disclosures made in said drawing and description, as many variations 30 may be introduced, within the spirit of this invention, as defined in the claims succeeding the said description.

The present structure is particularly adaptable to window openings fitted with 35 pivotal or casement window sashes, in which it is often necessary to fit the screen within the opening, in the interior portion of the window frame. The construction illustrated represents a combination of frames, inter- 40 connected and slidable upon each other in such a manner, that the combined thickness of the screen frames is kept within the limit of sightliness and the available space for installing the screen. It is important 45 also that the screen be easily opened, giving ready access to the window sashes; and that the whole screen may be quickly and easily removed from the window frame without leaving the window opening unsightly, by 50 reason of the nature of any permanent elements of the screen remaining, during that season of the year that window screens are unnecessary. The particular function of

such screens is to prevent the entrance of insect pests into dwellings.

55 In the one sheet of drawings: Figure 1 is a side elevation of a window frame in cross section, having a screen constructed in accordance with this invention installed therein, and shown in full lines. Fig. 2 is 60 a plan view from above of the screen in cross section taken on the line II—II. Fig. 3 is a fragmentary detail in front elevation of one side of the upper screen section. Fig. 4 is a side elevation of the same partially in 65 cross section, particularly illustrating the suspending hook and the spring friction member. Fig. 5 is an enlarged detail in perspective of the upper portion of the suspending hook engaging the supporting 70 bracket.

75 In detail the construction illustrated in the drawing includes the upper screen section, comprising a rectangular frame composed of top and bottom rails 1 and 2 joined by side stiles 3 and 4, mortised or otherwise joined at the corners to form an open frame. The opening in this frame is covered by suitable wire mesh or screen 5, stretched across the opening and secured around the 80 margins thereof by the top and bottom strips 6 and 7 and the side strips 8—8. The side stiles 3 and 4 are provided with the longitudinal shallow grooves 9—9, substantially equal in depth to the thickness of the 85 suspending hooks 10 and the friction springs 11 fixed therein, near the top and bottom respectively, of the upper screen section. These grooves 9 are easily and cheaply formed during the process of milling the 90 side stiles, and serve as gains for the hooks and the friction springs into the stiles flush with the surface thereof. These friction springs are provided with a raised portion 12, adapted to engage the contiguous portion of the adjoining screen section, to frictionally hold the two parts of the screen in the desired position on each other. The natural resilience of the friction springs 11 is supplemented by the expansion of the coil 95 springs 13, embedded in the side stiles 3 and 4. The side strips 8—8 are beveled on their outer edges to form an overhanging lip 14.

100 The lower screen section consists of a rectangular frame similar to the upper section, composed of top and bottom rails 15

and the side rails 16 and 17 suitably joined at the corners. The opening in the frame is closed by the wire mesh or netting 18, secured thereon by the molding strips 19 nailed to the frame. The guide strips 20 and 21 are securely nailed to the back of the side stiles 16 and 17, and have the overhanging lips 22 engaging the overhanging edge 14 of the strips 8—8, to form a dovetail 10 guide between the upper and lower screen sections, on opposite sides. These strips 8, 20 and 21 are preferably formed of hardwood, that being best adapted for the purpose, or they may be formed of metal with 15 the same functional characteristics. The exposed sides of the strips 20 and 21 are provided with the longitudinal grooves, coincident with the grooves 9 and into which the friction portion 12 of the springs 11 extend 20 and exert a retarding friction, when the lower screen section is raised or lowered across the upper section. When the screen is fully extended, that is, when the upper rail 15 of the lower section overlies the 25 lower rail 2 of the upper section, the maximum strain is exerted between the overhanging edges 14 and 22 of the strips 8, 20 and 21; to relieve these guide strips from the 30 danger of splitting, the plates 23 are attached by the screws 24 to the side stiles 3 and 4 overlapping the strips 8 and overhanging the extended edge thereof, engaging the rabbet formed in the edge of the strips 20 and 21. These metal strips have 35 a firm and substantial sliding engagement with the strips 20 and 21, securely holding the upper and lower sections together, and relieving the guide strips from undue strain.

In the drawings a screen having two sections is illustrated. It is obvious however, that a greater number of sections could be 40 similarly combined. The suspending hooks 10 engage the slots 25 in the brackets 26 attached to the stop 27, fixed across the top 45 of the window opening abutting the closed sash. Suspended from the brackets 26 the upper section hangs against the side stops 28, securely screening the upper half of the 50 window opening. The lower section of the screen attached to the upper section as described, similarly screens the lower half of the window opening, see Fig. 1. The screen is held in this vertical position by the round headed fixtures 29, driven into the 55 side stops 28 and engaging the grooves 30 formed in the edges of the side stiles 16 and 17 of the lower section; the entrance 31 to this groove is slightly flared to facilitate engagement with the guide fixtures. These 60 fixtures 29 are located high enough above the window stool 32 to permit the raising of the lower section of the screen, for the manipulation of the lower window sash X' without disengaging the lower section from 65 the guide fixtures. When it is necessary to

manipulate the upper sash X, the lower section of the screen is slid upward over the upper section, permitting the screen to swing outward on the hooks 10, permitting a free access to the whole window opening. 70 When it is desired to remove the screen for convenience in window washing or for any other reason, the collapsed screen is swung outward until the hooks 10 disengage from the slots in the brackets 26; the screen is restored to position by reversing this operation. 75

The window framing can be constructed for the reception of screens of this type by rabbeting the stops 27, 28 and 33 as shown 80 to perform the double function of acting as stops for the window sashes on the one edge, and stops for the screen on the other edge. For manufacturing reasons it is desirable to standardize the product as much as possible, 85 making one size of screen adaptable to as many window widths as may be; with this idea in view the screen is so constructed that a considerable width can be planed off of the sides of the screen, to fit it to a window 90 opening narrower than the standard width of the screen; for this reason the hooks 10 and the springs 11 are set in from the edge of the side stiles. Another mode of adapting the screen to the window opening, is to 95 provide special stops that may be trimmed down to the marginal space between the edges of the screen frames and the edges of the window opening.

It is preferable to manufacture the screen 100 frames of wood to match the window trimmings, to maintain a uniformity in appearance; however I contemplate carrying out the functional characteristics of this invention as shown and described, in metal and do 105 not therefore wish to be limited to the exact structure disclosed.

Having thus described this invention, what I claim and desire to secure by Letters Patent is:

1. A window screen comprising upper and lower sections, guide strips carried by the sections and in slidable engagement, said guide strips having complementary overlapping portions, and frictional guide members 115 attached to the face of one section and engaging the guide strips of the other section, the last mentioned guide strips being provided with portions complementary to said frictional guide members. 120

2. A window screen comprising upper and lower sections, guide strips carried by the sections and in slidable engagement, said guide strips having complementary overlapping portions, frictional guide members attached to the face of one section and engaging the guide strips of the other section, the last mentioned guide strips being provided with portions complementary to said frictional guide members, and reinforcing 130

plates attached to the guide strips of the other section adjacent said frictional guide members.

3. A window screen comprising a stationary upper section, a movable lower section, guide strips carried by the sections and in slidable engagement, said guide strips having complementary overlapping portions, frictional guide members attached to the face of one section and engaging the guide strips of the other section, the last mentioned guide strips being provided with portions complementary to said frictional guide members, and means for guiding the side edges of the lower section.

4. A window screen including upper and lower sections; overlapping strips secured to said upper and lower sections respectively; friction members interposed between said upper sections and the adjacent strip on the lower section; suspending hooks fixed on said upper section, adapted to engage brackets fixed in the window frame; and grooves in the lateral edges of said lower section engaging guide fixtures adapted to be fixed in the sides of the window frame.

5. A window screen including upper and lower sections; inside strips secured to said upper section and outside strips secured to said lower section and slidably engaging said inner strips; spring friction members fixed to said upper section and engaging

grooves in said outer strips; and resilient members embedded in said upper sections beneath said friction members.

35

6. A window screen including an upper section; inner strips secured to the sides of the upper section; a lower section; outer strips secured to the lower section and slidably engaging said inner strips; grooves in the face of said upper section near the sides thereof coinciding with grooves formed in said outer strips; suspending hooks fixed in said grooves near the top of the upper section; friction springs fixed in said grooves near the bottom of the upper section and frictionally engaging the grooves in the outer strips; and resilient members embedded in the upper section beneath said friction springs.

40

45

50

7. In combination with a window frame; a window screen having upper and lower sections slidably engaging each other; brackets fixed in the top of said frame; hooks engaging said brackets; and fixed to said window screen; guide fixtures fixed in the sides of said frame engaging grooves in the lateral edges of said lower section.

55

In testimony whereof, I have hereunto set my hand this 21st day of December, 1914.

ARTHUR C. SOULE.
